(12) **United States Design Patent** (10) **Patent No.:** **US D766,581 S**
(45) **Date of Patent:** **** Sep. 20, 2016**

(54) **ELECTRIC TOOTHBRUSH HANDLE**

(71) Applicant: **COLGATE-PALMOLIVE COMPANY**, Piscataway, NJ (US)

(72) Inventors: **Brian Bloch**, Hillsborough, NJ (US);
Lars Ralf Rainer Lieberwirth,
Glashuetten (DE)

(73) Assignee: **COLGATE-PALMOLIVE COMPANY**, New York, NY (US)

(**) Term: **14 Years**

(21) Appl. No.: **29/477,152**

(22) Filed: **Dec. 19, 2013**

(51) LOC (10) Cl. **04-02**

(52) U.S. Cl.

Primary Examiner — Lisa A Grabenstetter

(57) **CLAIM**

The ornamental design for an electric toothbrush handle, as
shown and described.

DESCRIPTION

FIG. 1 is a front perspective view of a first embodiment of
an electric toothbrush handle showing our new design;
FIG. 2 is a rear perspective view thereof;
FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is a front perspective view of a second embodiment

of an electric toothbrush handle showing our new design;

FIG. 10 is a rear perspective view thereof;

FIG. 11 is a front view thereof;

FIG. 12 is a rear view thereof;

FIG. 13 is a right side view thereof;

FIG. 14 is a left side view thereof;

FIG. 15 is a top plan view thereof; and,

FIG. 16 is a bottom plan view thereof.

The broken lines and the areas within the broken lines shown
on the top and bottom of the article in FIGS. 1-16 illustrate
portions of the electric toothbrush handle that form no part
of the claimed design while the broken lines and the areas
within the broken lines shown on front and rear of the article
in FIGS. 9-16 illustrate portions of the electric toothbrush
handle that form no part of the claimed design.

1 Claim, 8 Drawing Sheets
